UNITED STATES PATENT OFFICE.

FRANK W. SMITH, OF TULSA, OKLAHOMA, ASSIGNOR, BY DIRECT AND MESNE ASSIGNMENTS, OF ONE-FOURTH TO WILLIAM E. ALLISON AND ONE-FOURTH TO WASH E. HUDSON, BOTH OF TULSA, OKLAHOMA.

OIL-BURNER.

1,157,332.

Specification of Letters Patent.

Patented Oct. 19, 1915.

Application filed June 23, 1915. Serial No. 35,802.

To all whom it may concern:

Be it known that I, FRANK W. SMITH, a citizen of the United States, residing at Tulsa, in the county of Tulsa and State of Oklahoma, have invented certain new and useful Improvements in Oil-Burners, of which the following is a full, clear, and exact description, reference being had to the accompanying drawings, forming a part hereof.

My invention has relation to improvements in oil burners; and it consists in the novel construction of burner more fully set forth in the specification and pointed out in the claim.

The present improvement is more particularly directed to burners operating on hydrocarbons such as crude petroleum, gasoline, kerosene and the like, the object being to provide the burner with a vapor generator which will prevent any material drop in the temperature of the vapor discharged therefrom on its way to the mixing chamber, the present improvement contemplating the simultaneous heating of the walls of the generator member as well as the member into which the mixture of air and vapor is discharged from the mixing chamber, said member in the present construction constituting the burner head or cap as presently to be seen.

A further object is to provide means of effecting an even distribution of the mixture to the burner head; to provide effective means against leakage by the elimination of screw joints; to provide a burner which may be attached to any existing coal or wood-burning stove; one which is simple, cheap and durable, and one possessing further and other advantages better apparent from a detailed description of the invention in connection with the accompanying drawings, in which—

Figure 1 represents a side elevation of a conventional stove body showing my invention applied thereto; Fig. 2 is a side elevation of the burner, with fuel-feed pipe in cross-section and with part of the burner head removed; Fig. 3 is a top plan of the burner with the bulk of the burner head removed; Fig. 4 is a vertical cross-section on the line 4—4 of Fig. 3; and Fig. 5 is a vertical longitudinal section on the line 5—5 of Fig. 3.

Referring to the drawings, S represents a conventional coal stove and F the fire pot thereof as well understood in the art. Adapted to be inserted into the fire-pot and secured therein in any mechanical manner is my improved burner, the same comprising a plate or disk 1 provided with a central opening O, said plate forming a supporting platform for the deflector or distributor member 2 mounted directly above the opening, and secured to the platform through the feet a. Depending from the edge of the plate 1 is a boss 3 traversed by a central passage-way or duct h whose upper end or that adjacent the platform 1 is enlarged to receive an inner plug of Babbitt metal m and outer plug of fire-proof cement n, said plugs receiving the discharge terminal 4 of the vaporizer coil or conduit 4' disposed contiguous the outer edge of the platform 1. Preferably, the terminals of the feet a of the distributor 2 are interposed between the coil 4' and platform 1. The coil 4' is provided with an intake extension 4'' disposed in the general plane of the coil, said extension passing through an arm or boss 5 formed with the platform 1, and extending into the discharge end of the fuel-feed pipe P screwed into said boss. The outer terminal of the boss 5 is formed with a socket for receiving a perforated plug 6 of Babbitt metal through which the pipe 4'' passes and against which the inner end of the pipe P abuts, the babbetting of the pipe 4'' to the plug 6 making an absolutely tight or leak-proof joint. At the inner end of the boss 5 is likewise formed a socket for receiving an inner perforated Babbitt plug 7 and an outer ring of fire proof cement 8 through which the pipe 4'' passes, the babbetting of the pipe 4'' to the plug 7 likewise insuring a leak-proof joint.

Leading from the lower terminal of the boss 3 is a horizontal leg 3' provided with a passage-way h' communicating with the passage-way or duct h of the boss 3, the outer end of the passage h' terminating in an enlargement h'' from which leads a discharge port t formed in the wall of the leg 3', the axis of the port being coincident with the axis of the opening O through which the mixture of vaporized oil and air formed in the air gap G is projected against the distributor or deflector 2. The gap G serves as,

and performs the function of, a mixing chamber as obvious from the drawings. The discharge terminal of the duct h' is controlled by a needle valve v at the inner terminal of a screw valve stem 9 operating in a stuffing-box 10 at the outer end of the leg 3', the stem 9 being extended to pass through the front of the stove S, and terminating on the outside in a handle 9' by which the stem may be manipulated and thus the flow of the vapors from the duct h' controlled. As seen from the drawings, the axes of the leg 3' and boss 5 are at right angles to one another, but disposed in parallel planes. 15 Surmounting the plate or platform 1 is a dome or arch shaped burner head or cap B provided with burner openings o, the edge of the burner-head resting on the plate 1 adjacent the periphery of the latter, as shown, the walls of the burner head being spaced from the deflector 2 and the arms a thereof, and forming with the supporting platform 1 a collecting chamber C for the mixture which pours through the openings o. Secured to the bottom of the boss 3 beneath the leg 3' is a starting pan or equivalent holder H for alcohol or other fuel by 20 the burning of which the walls of the leg 3' are initially heated to properly start the 25 burner.

The operation of the burner is substantially as follows: Alcohol having been first poured into the pan H is ignited thereby insuring the heating of the walls of the leg 3'. The valve v is then moved to open position (the liquid hydrocarbon or fuel being previously turned on to flow into the pipe P), the oil thus flowing through the pipe 4", coil 4', extension 4, passage h , and passage h' , and being vaporized by its contact with the heated metal of the burner. The vapor is projected from the port t across the gap G forming the mixing chamber into the collecting or distributing chamber C 40 through the opening O, escaping through the burner openings o when the same may be ignited. In traveling across the gap G, the proper complement of air is caused to mix with the vapor so that when the mixture 45 is ignited at the openings o it burns with a 50

bright blue flame. Once ignited, the flame issuing from the burner head heats up the several parts of the burner so that upon exhaustion of the contents of the pan H, the liquid will be vaporized in its traverse through the members 4", 4', 4, h , h' .

I may of course depart in a measure from the details here shown without in any wise affecting the nature or spirit of the invention. Preferably, the boss 5 is removed angularly from the leg 3 (in the present instance ninety degrees) so as to discharge into the chamber C in a direction transverse to the leg 3', this arrangement being essential for obvious reasons, particularly to permit of the proper installation of the burner in the fire box F of the stove. 60 65

Having described my invention what I claim is:

In a burner of the character described, a suitable platform, a vaporizer conduit mounted on top of the same and discharging through and to one side thereof, a member carried by the platform and provided with a passage-way for receiving the discharges from said conduit, a leg leading from the member aforesaid beneath the platform and spaced a suitable distance therefrom, said leg being provided with a passage-way forming a continuation of the passage-way of the member aforesaid, the walls of the leg being provided with a port leading from the passage-way thereof and discharging into and across the space between said leg and platform, the latter being provided with an opening traversable by said discharges, a burner head surmounting the platform and inclosing the vaporizer conduit, a distributor supported by the platform within the burner head and having a central portion spaced from the platform and from the burner head, and means for controlling the discharges from the port of the leg aforesaid. 70 75 80 85 90

In testimony whereof I affix my signature, 95 in presence of two witnesses.

FRANK W. SMITH.
